UNITED STATES PATENT OFFICE.

FRANKLIN E. ARNDT, OF GALION, OHIO, ASSIGNOR TO THE GALION IRON WORKS & MFG. CO., OF GALION, OHIO, A CORPORATION OF OHIO.

CONVEYER AND DRIVING MECHANISM THEREFOR.

Application filed November 4, 1922. Serial No. 599,077.

To all whom it may concern:

Be it known that I, FRANKLIN E. ARNDT, a citizen of the United States, residing at Galion, in the county of Crawford and State of Ohio, have invented certain new and useful Improvements in Conveyers and Driving Mechanisms Therefor, of which the following is a specification.

This invention relates to conveying mechanism, and particularly to certain improvements upon the construction illustrated in my pending application for patent, Serial No. 546,756, filed on March 25, 1922, patented on December 5, 1922, #1,437,581.

In this patent, I disclose an elevator and a conveyer associated therewith for the purpose of conveying coal, crushed stone, slag, gravel or like material from beneath a railroad car and elevating the coal or other material, the conveying mechanism comprising two endless conveyers having outwardly extending blades moving over the surface of a plate disposed to rest upon the railroad tracks and beneath the bottom of the car. In this construction, the conveyer is disclosed as being driven from driving mechanism disposed beneath one end of the conveyer and within a pit. There was also disclosed a variant of this construction, wherein the driving mechanism was disposed above one end of the conveyer instead of below and detachably connected thereto, but the driving mechanism had to be disconnected from the elevator from which it was driven and also disconnected from the conveyer in order to permit the conveyer to be moved from place to place.

One of the objects of the present invention is to provide a construction of this character wherein the conveyer is driven from driving mechanism located above one end of the conveyer, thus doing away with the necessity of any pit for the lower end of the elevator and for the driving mechanism of the conveyer.

A further object is to provide a driving mechanism which is operatively connected to the elevator by such means that the driving mechanism may be disconnected from the conveyer and turned back upon the elevator and moved with the elevator as a unit.

A still further object is to improve the details of construction of the conveyer and

of the driving mechanism and adapt the conveyer to be used with a portable elevator or conveyer mounted on wheels so that they may be shifted from one point to another to thus permit the apparatus to be conveniently handled and conveniently put in position.

Other objects will appear in the course of the following description.

My invention is illustrated in the accompanying drawings, wherein:

Figure 1 is a side elevation of my conveyer and coacting elevator, the track rails being shown in section;

Figure 2 is a fragmentary top plan view of the construction shown in Figure 1;

Figure 3 is a longitudinal sectional view on the line 3-3 of Figure 4;

Figure 4 is a top plan view of one of the horizontal conveyers, the upper plate being removed;

Figure 5 is a top plan view of the frame for supporting the driving gears and the gears associated therewith;

Figure 6 is a vertical longitudinal section on the line 6-6 of Figure 5;

Figure 7 is an end elevation of the construction shown in Figures 5 and 6;

Figure 8 is a section on the line 8-8 of Figure 6;

Figure 9 is a front elevation of the superstructure of the elevator and a portion of the frame shown in Figure 5;

Figure 10 is a perspective view of one of the scraper or attachment links.

The conveyer comprises a steel plate 10 having any desired area and adapted to extend over and rest upon the rails A of a railroad track and be shiftable from place to place. This plate 10, as illustrated in Figure 1, is provided upon its under side with stops 11 spaced from each other the gauge of the track so as to rest against the inside faces of the rails and hold the plate 10 from shifting after it is put in position. Mounted upon the plate 10 are two conveyers, each having an endless conveyer chain moving parallel to the upper face of the plate, and having blades which move over the face of the plate and carry the material dumped upon the plate toward the discharge end of the plate. Both of these conveyers are of the same construction,

therefore, the description of one will apply to the other. Each conveyer consists of an upper plate 12 and a lower plate 13, these plates being rounded at their ends. These 5 plates are held spaced from each other by a longitudinally extending filler block 14 of wood or any other suitable material, bolts 14^a passing through the filler blocks and the two plates and holding the filler blocks in 10 place.

Extending longitudinally between the two plates and between the filler blocks is a pipe section 15 which is held in place by straps 16 which embrace the pipe section and have 15 laterally extending ears through which bolts 17 pass, these bolts passing through the upper and lower plates. Thus the pipe section 15 is held rigidly in place between the two plates. Inserted into one end of the pipe 20 section 15 is a tubular shank 18 formed with a bifurcated yoke 19 at one end, this yoke having a bearing 20. The shank 18 is adapted to telescopically shift within the pipe section 15. Mounted within the bearing 25 ings 20 is a gudgeon 21, surrounding which is a bushing 22, and rotatably mounted upon this bushing and within the yoke 19 is a sprocket wheel 23. A bolt 24 passes through a washer 25 and through a slot 26 formed in 30 the upper plate 12 and axially through the gudgeon 21 and through a slot 26 in the lower plate 13. The aperture 20 in the upper arm of the bifurcated yoke 19 is many-sided in cross section and the upper extremity of the gudgeon 21 is many-sided in cross section and fits this aperture so that the gudgeon 21 does not turn but the sprocket wheel 23 rotates with reference to this gudgeon.

The strap 16^a which is disposed at the adjacent extremity of the pipe section 15, and which is formed with a flange 27 preventing longitudinal movement of the pipe section, is formed on each side of the pipe section with screw-threaded apertures 28 for the 40 passage of adjusting screws 29. These adjusting screws bear against the head 30 of the yoke 19, and by this means the yoke, together with the sprocket wheel, may be shifted outward so as to thereby stretch or 45 tighten the conveyer chain which passes around the sprocket wheel. Apertures 31 are formed in the lower face of the plate 13 whereby access may be had to the heads of the adjusting screws 29 to turn up or retract these adjusting screws.

At the opposite end of the pipe section 15 there is provided a yoke 32 of the same general character as the yoke 19 having two 50 bearings which are spaced from each other and provided with the two bushings 33, and disposed within the bushings and rotatable therein is the hub 34 of a sprocket wheel 35. It will be seen from Figure 3 that the plate 12 extends slightly over the hub of the 55 sprocket wheel so that this sprocket wheel is

held from axial movement. This sprocket wheel is formed with a central, square passage 36 and the plate 12 is formed with an aperture somewhat larger than and concentric to the passage 36.

The endless chain which passes around the sprocket wheels 23 and 35 is made up of a plurality of pivoted links 37 and at intervals there are disposed the attachment links 38 formed to provide outwardly extending 70 blades 39. While I do not wish to be limited to the exact shape of these blades, these blades are preferably made as illustrated in Figure 1 with a solid base 38 forming the link proper, the upper face of this base extending downward, the blade 39 having a flat under face resting upon the base plate 10, and the upper face of the blade being laterally rounded. The object in so forming the blade is to prevent breaking or 75 grinding soft coal, when this device is used as a coal conveyer, or for operating on relatively friable materials. The rounded upper surface of the blade will move beneath the coal, where the lump of coal is not readily shifted by the blade, and will pass beneath the lump until eventually the lump of coal is shifted by other coal backing up behind it and thus taken off of the plate 10. I have found in actual use that the shape of 80 these blades is quite important, particularly where materials like soft coal are to be handled, and that this particular shape of blades prevents the breaking up of the lumps of 85 soft coal and the grinding of the particles 90 into dust.

As before remarked, there are two conveyers constructed as I have just described, these conveyers resting upon the upper face of the plate 10 and being pivoted at their outer ends to the extension of the plate 10 beyond the tracks so that the conveyers may be shifted from a divergent position into a parallel position or even into a convergent position. It will be seen that the sprocket 105 wheels 35 are operated so that the endless conveyers will be carried in the direction of the arrows in Figure 2 and that the blades will sweep all materials upon the face of the plate toward the discharge end of the plate. 110

The materials from the upper face of the plate 10 are discharged into an elevator or conveyer whereby the materials are carried upward for discharge into trucks or into other suitable receptacles, and I have illustrated in connection with the conveyer an elevator mechanism including a supporting frame mounted upon wheels so that it may be readily transported from place to place, this supporting frame having mechanism 115 whereby the inclination of the elevator may be varied and supporting an endless elevator driven by a motor forming part of the frame and the elevator including a counter-shaft 40 carrying a sprocket wheel 41, from 120

which passes an endless drive chain 42 whereby the endless chains of the horizontal conveyers may be driven.

In order to provide for a detachable operative engagement between the horizontal conveyers on the plate 10 and the elevator, I provide a substantially rectangular frame formed of longitudinal members 43 connected by transverse members and supported at its opposite ends by yoke arms 44 extending laterally in opposite directions from a hollow supporting column 45. The lower end of this column is flanged, as at 46, so that the lower ends of the columns rest upon the upper plates 12 of the two conveyers. Passing vertically through each column and rotatably mounted in bearings 47 therein is a vertical shaft 48. The lower end of this shaft is square or many-sided in cross section and is larger than the body of the shaft, and this square portion of the driving shaft is adapted to be inserted in a square or many-sided socket 36 in the sprocket wheel 35. This squared portion 49 of the shaft 48 is of such length that it extends below the plate 13 and is supported in an annular bearing 50 bolted or otherwise attached to the plate 10 and supporting within it a bushing 51. The lower end 49 of the shaft 48 is downwardly tapering so as to permit the ready insertion of the shaft within the aperture in sprocket wheel 35. The upper end of each shaft 48 carries upon it a beveled gear-wheel 52.

The members 43 are formed of angle irons bolted to the arms 44 of yokes carried by the columns 45 and bolted at intervals to the horizontal flanges of the angle irons 43 are angular hangers 53, to which the sectional bearing boxes 54 are bolted, each bearing box having an interior bushing 55 and a lubricating cup 56 formed therewith. Disposed in these bearings and extending longitudinally along the frame formed of the members 43 and the connecting braces is a shaft 57. This shaft, as illustrated, extends beyond the ends of the frame and carries upon it the beveled gear wheels 58 which engage with the beveled gear wheels 52 so as to drive the shafts 48. Engaging the projecting ends of the shaft 57 are sleeves 59 having bushings immediately surrounding the shaft, and provided with the oil or lubricant cup 60. Each of these sleeves is formed with a socket member 61, and inserted between both the socket members and bolted thereto by bolts 62 are the links 63, these links at their ends remote from the point of attachment to the shaft 57 being inserted in socket members 64 having integral sleeves 65 through which the counter-shaft 40 passes. Thus these links are pivoted to the shaft 40 concentric to the driving sprocket wheel 41 and are pivoted to the shaft 57 concentric to the driven sprocket wheel 66 thereon, this sprocket wheel 66 being attached at one end of the shaft 57, as illustrated in Figure 6. Thus it will be obvious that the frame supporting the shaft 57 is held by these links 63 at all times in proper driving relation to the counter-shaft 40 and that the shafts 48 are thus supported so that the lower ends of these shafts may be readily inserted in the apertures, or sockets 36 of the sprocket wheels 35 or readily removed therefrom as a unit and without the necessity of taking off the sprocket chain 42 or in any way disassembling any of the parts of the drive gear. Thus when it is desired to disengage the driving gear from the conveyers operating over the plate 10, it is simply necessary to lift up on the links 63, which will raise the shafts 48 from their engagement in the sockets 36, and then this driving gear supported in the frame 43 may be turned over on top of the elevator and the plate 10 with its conveyers shifted to any desired position and the elevator shifted to any desired position. After the parts have been shifted to a new position, it is an easy matter to shift the links 63 over to bring the driving gearing again in proper engagement with the sockets 36 to operate the conveyers over the face of the plate 10.

While I do not wish to be limited to the use of the drag conveyer which I have previously described with any particular form of elevator, I have illustrated the lower portion of an upwardly inclined elevator or conveyer of an ordinary type, wherein there are used lateral frames 67 supporting the upper and lower flights of the two laterally disposed chains 68 carrying transverse blades. These blades travel over upper and lower troughs 69. Mounted upon the frame is the counter-shaft 40 previously described, which carries upon one end a sprocket wheel 70 whereby power is transmitted to the shaft 40 from any suitable source of power, this shaft 40 in turn through the sprocket wheel 41 and chain 42 transmitting power to the driving mechanism for the drag conveyers operating over the plate 10. I have illustrated only so much of the elevator as will serve to illustrate the manner of connecting the driving mechanism for the drag conveyers with the elevator and I do not wish to be limited to any particular form of elevator or conveyer in association with the drag conveyers operating over the plate 10, it being obvious that the links 63 might be mounted upon a counter-shaft or drive shaft 40 of any suitable elevating mechanism. The details of the elevator or conveyer which I particularly design to be used in connection with the drag conveyer are fully illustrated and described in my pending application for patent, Serial No. 599,078, filed on the 4th day of November, 1922.

The general operation of the mechanism heretofore described will be obvious. With this construction, each drag conveyer formed of the plates 12 and 13 and the conveyor chains having blades 39 is operatively pivoted to the corresponding shaft 48 for oscillation across the face of the plate 10 and thus it will be obvious that the conveyers may be shifted from a parallel to an outwardly divergent relation or an outwardly convergent relation, as the circumstances of the case require. Thus, for instance, when the load is first discharged from the railway car or other source of supply onto the plate 10, the drag conveyers may be disposed in a widely divergent relation, and then as the material is conveyed to the elevator and moved from the face of the plate 10, the drag conveyers may be shifted toward each other so as to eventually remove every bit of material from the face of the plate. When it is desired to shift the apparatus, the frame supporting the horizontal shaft 57 and the vertical shafts 48 is lifted up so as to lift the portions 49 of the shafts 48 from the sockets 35 and then this frame with the driving gears thereon is shifted over on top of the elevator and then the elevator may be trundled to the place desired and set up again. The drag conveyers are laid upon the face of the plate with their openings 36 coinciding with the openings in the plate 10 and then the driving gear unit is raised from the elevator and brought over so as to carry the shafts 48 into alignment with the sockets 35 and the shafts are then forced down into these sockets and into the bearings 50 and 51 carried on the under side of the plate 10. When this has been accomplished, the driving mechanism for the elecator is started up, which, through the chain 42, operates upon the driving mechanism of the drag conveyers.

While I do not wish to be limited to any particular means for raising or lowering the driving gear frame 43 around the axis formed by the counter-shaft 40, I have illustrated a block and tackle mechanism for this purpose. The elevator frame is mounted between uprights 71 connected at their upper ends by a cross piece 72, the lower ends of these uprights being operatively connected to the axles 73 upon which the supporting wheels 74 are mounted. The lower ends of the uprights 71 are connected by a transversely extending cross piece 75 which extends out beyond these uprights 71, and braces 76 are pivotally connected by any suitable means, not forming part of this invention, to the elevator frame and to this

cross beam 75. Thus the elevator frame is mounted for pivotal movement upon the forward ends of the braces 76 and thus the elevator may be disposed at any desired inclination. To this end an elevating yoke, 70 designated generally 77, is connected to the elevator and carries a block 78, while a pulley 79 is mounted on the cross piece 72 at the middle thereof and another pulley 80 is mounted at one end of the cross piece 72. 75 The cable passes from a drum 73 over the pulley 80, thence over the pulley 79, down to and around the pulley and the block 78, then up over a second pulley 79, and then down to the yoke 77. Thus it will be obvious that by rotating the drum 73 in one direction or the other that the elevator will be raised or lowered.

For the purpose of raising or lowering the frame supporting the driving shaft 57, I mount upon one of the frame bars 43 the two pulley blocks 81 and 82. A cable 83 is attached to one end of the cross beam 72, then extends downward and around the pulley block 81, then upward to the cross beam and over a pulley 84 attached thereto, then across the cross beam 72 to a pulley 85, then down and around the pulley 82, then upward and over a pulley 86 attached to the end of the cross piece 72, and then down to a drum 87 suitably supported upon the beam 75 and the adjacent upright 71. This drum is preferably operated by means of a worm shaft 88 having a crank whereby it may be rotated. Any other suitable means may be used for this purpose. Thus whenever it is desired to detach the driving mechanism from the drag conveyers, the drum 87 is operated to lift the frame 43 and an operator guides the lower portions of the shafts 49 and the shafts 48 out of the sockets 35 until the shafts are entirely detached from the sockets. The elevator then may be trundled to any desired position and when it is desired to again use the elevator the drum is turned reversely to permit the unwinding of the cable 83 and the lowering of the links 63 and the frame supporting the driving shaft, the operator guiding the lower ends of the shafts 48 into the sockets in the conveyers in an obvious manner.

It will be noted that the conveyers are separate from and merely rest upon the plate 10 so that the conveyers may be separately transported to the position desired and the plates separately transported, laid down, the conveyers put in place thereon with the sockets of the conveyers immediately over the bearings for the vertical shafts in said plate, then the driving frame lowered to 125 carry the lower ends of the vertical shafts into said sockets and bearings, and the mechanism is in position for operation.

The particular advantage of my construction over that illustrated in my Patent 120

#1,437,581 is that the driving mechanism for the drag conveyers is removable as a unit from engagement with the drag conveyers and shiftable as a unit upon the elevator frame for transportation, and that the links which guide and support the driving mechanism for the drag conveyers as it is being shifted hold the sprocket wheels 41 and 66 in properly spaced relation and, therefore, hold the chain 42 taut and do away with the necessity of taking off this chain.

While I have shown a base plate 10 which is of thin metal, which may be readily removed from place to place, it will be obvious that a platform might be built between or on a level with the upper faces of track rails and the conveyers be disposed upon said platform after a car had been run over the platform to the proper discharge point. I consider a permanent platform, therefore, as being broadly the equivalent of a base plate upon which the conveyers will operate.

25 While I have illustrated certain details of construction and arrangement of parts which I believe to be preferable, I do not wish to be limited thereto, as these details may be varied without departing from the spirit of the invention as embodied in the appended claims.

I claim:

1. A conveyer mechanism including a plate, a pair of endless conveyers operating thereover and driving means therefor including a pair of shafts having detachable driving engagement each with one of said conveyers, a driving shaft common to both of said first named shafts and geared thereto, and a frame supporting said driving shaft and the first named shafts in driving relation with the driving shaft and in parallel relation to each other whereby the driving shaft and the first named shafts may be engaged with or disengaged from the endless conveyers as a unit.

2. A conveyer mechanism comprising a plate, an endless conveyer operating thereover and including a rotatable member having a socket, and driving means therefor comprising a supporting frame normally disposed above the face of the plate having a tubular column adapted to rest upon the face of the plate, and a shaft extending through the tubular column and projecting therebeyond and adapted to be detachably engaged in said socket.

3. A conveying mechanism comprising a plate, an endless conveyer operating over and parallel to the face of the plate and having outwardly projecting blades and including a rotatable driving member having a socket, and means for driving the conveyer comprising a supporting frame normally disposed above the plate and having

a downwardly projecting tubular column adapted to be disposed upon the conveyer at its lower end, and a shaft extending through said column and formed to have operative driving engagement with said 70 socket.

4. A conveyer mechanism comprising a supporting plate, an endless conveyer operating thereover and comprising upper and lower plates, sprocket wheels rotatably carried between the ends of said plates, a sprocket chain extending around the sprocket wheels and having blades, and driving means therefor comprising a power operated shaft, the shaft and one of said 75 sprocket wheels having detachable operative engagement.

5. A conveyer mechanism comprising a plate, a conveyer operating thereon and comprising upper and lower supporting 85 plates, sprocket wheels disposed between said plates at the ends thereof, an endless chain having blades and engaged by the sprocket wheels, one of said sprocket wheels having a socket and the upper face having 90 an opening coincident with said socket, and means for driving the endless conveyer comprising a supporting member having a hollow column adapted to rest upon the upper plate of the conveyer concentric to the opening therein, and a power operated shaft disposed within said column and projecting beyond the column and having detachable 95 driving engagement in said socket.

6. A conveyer mechanism comprising a 100 plate, a pair of endless conveyers operating thereover and each including a rotatable member having an axial socket in its upper face, a plate extending over said member and having an opening registering with the 105 socket, and means for driving both of said conveyers simultaneously comprising a supporting frame having tubular columns adapted to rest upon said last named plate concentric to the opening therein, a power 110 driven shaft mounted in said frame and having beveled gear wheels, and vertical shafts mounted in the frame and carrying coacting beveled gear wheels, the vertical shafts extending through the hollow 115 columns and below the same and being formed at their lower ends to have driving engagement with said sockets.

7. A conveyer mechanism including a supporting plate, an endless conveyer carried 120 upon the face of the plate and operating thereon and including a rotatable element having a socket, driving mechanism therefor including a structure having a power operated shaft, a rigid link extending from 125 and rotatable around the axis of the power operated shaft, a gear supporting frame mounted upon the link remote from the power operated shaft, a conveyer drive shaft carried by the frame and adapted to have 130

- detachable driving engagement with said rotatable element, and power transmitting mechanism operatively connecting the power operated shaft to the conveyer driving shaft at all times. 70
8. A conveyer mechanism including a supporting plate, an endless conveyer carried upon the face of the plate and operating thereover and including a rotatable driving element, a driving shaft therefor adapted to have detachable driving engagement therewith, a power operated shaft having operative driving engagement with the said driving shaft, and means for supporting the conveyer driving shaft and swinging it as a unit concentric to the power operated shaft out of or into engagement with the driving element on the conveyer. 75
9. A conveyer mechanism including a supporting plate, an endless conveyer carried upon the face of the plate and operating thereover including a rotatable driving element, a driving mechanism therefor including a structure having a power operated shaft, rigid links extending from and rotatable around the axis of the power operated shaft, a supporting frame pivotally mounted upon the extremities of the links, a conveyer drive shaft carried by the frame and adapted to have detachable operative driving engagement with said rotatable element on the conveyer, and power transmitting mechanism disposed between the drive shaft and said power operated shaft and connecting the power operated shaft with the conveyer drive shaft at all times, the links permitting the structure carrying the conveyer drive shaft to be rotated around the power operated shaft as a center into or out of driving association with said conveyer. 80
10. A conveying mechanism comprising a supporting plate, a pair of elongated endless conveyers carried upon the face of the plate and operating in a plane parallel thereto and each including a rotatable element, an elevator into which said plate discharges and including a supporting frame, a power operated shaft extending transversely of the frame and mounted thereon, a pair of links pivotally mounted on the power operated shaft for rotation therearound, a frame pivotally supported upon the extremities of the links, vertically disposed conveyer driving shafts operatively mounted upon the frame and each adapted to have detachable driving engagement with the rotatable element of the corresponding conveyer, and power transmission mechanism operatively connecting the power driven shaft with the conveyer driving shafts at all times. 85
11. In a mechanism of the character described, a conveyer and means for driving it comprising a power shaft, a drive shaft, transmission mechanism having driving en- 90
- gagement between the power shaft and the conveyer drive shaft at all times, the conveyer drive shaft being supported in permanent relation to the power operated shaft and being movable into operative engagement or removable from operative engagement with the conveyer as a unit. 95
12. In a mechanism of the character described, conveying mechanism including a supporting plate and an endless conveyer carried upon the face of the plate and operating thereover and including a rotatable element, and driving mechanism for the rotatable element movable into or out of engagement therewith as a unit. 100
13. A conveyer mechanism including a supporting plate, a pair of endless conveyers carried upon the face of the plate and operating in a plane parallel thereto and each including a rotatable element, an elevator, a second conveyer associated with the first named conveyer and upon which said plate discharges, a power operated shaft associated with the second named conveyer and carrying a sprocket wheel, rigid links rotatably mounted upon opposite ends of said shaft, a supporting frame rotatably mounted upon the extremities of said links, a longitudinal shaft carried thereby and having a sprocket wheel, a sprocket chain operatively connecting said sprocket wheels on the power shaft and last named shaft, tubular columns carried by said frame and extending downward therefrom, and drive shafts disposed within said columns and projecting below the same and each having operative driving engagement with the longitudinal shaft mounted in said frame, said drive shafts being adapted to have detachable operative driving engagement with said rotatable elements. 105
14. A conveyer comprising upper and lower elongated plates held in spaced relation to each other, a hollow member extending longitudinally between said plates, sprocket wheel supporting yokes disposed between said plates and having shanks insertible into the ends of said hollow member, one of said shanks having sliding engagement therewith, sprocket wheels carried by said yokes and disposed between the plates, an endless chain having outwardly projecting blades and mounted upon the sprocket wheels, and means for tightening the chain comprising screws operatively supported between said plates and operatively engaging against one of said yokes to force the yoke longitudinally. 110
15. A conveyer comprising upper and lower elongated plates held in spaced relation to each other, a hollow member extending longitudinally between said plates, sprocket wheel supporting yokes disposed between said plates and having shanks insertible into the ends of said hollow mem- 115
- 120
- 125
- 130

ber, one of said shanks having sliding engagement therewith, sprocket wheels carried by said yokes and disposed between the plates, an endless chain having outwardly projecting blades and mounted upon the sprocket wheels, means for tightening the chain comprising screws operatively supported between said plates and operatively engaging against one of said yokes to force 5 the yoke longitudinally, said upper and lower plates being slotted at one end, a retaining bolt passing through the slots and through the center of the corresponding sprocket wheel, and a washer bearing upon 10 the face of one of said plates and against which the nut of said bolt bears.

16. In a conveyer, upper and lower plates, means spacing the plates from each other, a longitudinally extending member having 20 yokes at its ends disposed between said plates and held in rigid position relative thereto, sprocket wheels carried in said yokes adjacent the ends of the plates, an endless sprocket chain passing around the sprocket 25 wheels and having outwardly projecting blades, and means whereby the distance between the sprocket wheels may be increased or decreased to thereby adjust the chain.

17. In a conveying mechanism of the character described, a supporting plate, an endless conveyer mounted upon the face thereof for movement parallel thereto and including an endless linked element including attachment links, each having an outwardly projecting blade, the lower face of the blade confronting said plate being flat and the upper face of the blade being laterally rounded.

18. A conveying mechanism of the character described comprising a supporting plate, a pair of conveyers mounted upon the plate and each consisting of upper and lower elongated plates held in spaced relation to each other, yokes operatively supported between said plates adjacent the ends thereof, sprocket wheels mounted in said yokes, one

of said sprocket wheels having a many-sided socket extending entirely through it, the base plate having an open-ended bearing attached at its under face coincident with 50 the socket in said sprocket wheel, power operated means for driving said conveyers comprising a supporting frame, a power operated shaft rotatably mounted in the frame, driving shafts extending downward from 55 the frame and operatively geared to the power operated shaft and insertible into said sockets and into the bearings in the base plate, and tubular members forming part of the frame and through which said shafts 60 extend and adapted to rest upon the upper face of each upper conveyer plate.

19. A conveying mechanism of the character described comprising a supporting plate, a pair of conveyers mounted upon the plate and each consisting of upper and lower elongated plates held in spaced relation to each other, yokes operatively supported between said plates adjacent the ends thereof, sprocket wheels mounted in said yokes, one 70 of said sprocket wheels having a many-sided socket extending entirely through it, the base plate having an open-ended bearing attached at its under face coincident with the socket in said sprocket wheel, power operated 75 means for driving said conveyers comprising a supporting frame including longitudinally extending members and transverse members having bearings, yokes connected to and extending below the longitudinal 80 members, said yokes supporting hollow, depending columns, a longitudinal power operated shaft mounted in said bearings, vertical shafts mounted in said columns and 85 operatively geared to the longitudinal shaft, said vertical shafts extending below the columns and being formed at their lower ends to have driving engagement with the sockets in said sprocket wheels and to extend into the bearings in the base plate. 90

In testimony whereof I affix my signature.
FRANKLIN E. ARNDT.
